(57) **CLAIM**

The ornamental design for a door opener lever, as shown and
described.

DESCRIPTION

FIG. 1 is an isometric view of a door opener lever showing
our new design;

FIG. 2 is a front view of FIG. 1;

FIG. 3 is a bottom view of FIG. 1;

FIG. 4 is a left side view of FIG. 1;

FIG. 5 is a right side view of FIG. 1;

FIG. 6 is an isometric view of the door opener lever of FIG.
1 without a keyhole;

FIG. 7 is a front view of FIG. 6;

FIG. 8 is a bottom view of FIG. 6;

FIG. 9 is a left side view of FIG. 6; and,

FIG. 10 is a right side view of FIG. 6.

The broken-line disclosure in the views is for illustrative
purposes only and forms no part of the claimed design.
